UNITED STATES PATENT OFFICE.

CORNELIUS CHIPPENDALE, OF AUBURN, MAINE.

LOOM-PICKER.

SPECIFICATION forming part of Letters Patent No. 417,665, dated December 17, 1889.

Application filed August 21, 1889. Serial No. 321,466. (No model.)

To all whom it may concern:

Be it known that I, CORNELIUS CHIPPENDALE, of Auburn, in the county of Androscoggin and State of Maine, have invented a new and Improved Loom-Picker, of which the following is a full, clear, and exact description.

This invention relates to loom-pickers, the main object of the invention being to provide a simple, cheap, and durable picker, and one which may be readily connected to the picker-staff.

To the ends named the invention consists, essentially, of a housing and a means for connecting the housing to the picker-staff, the housing being formed to receive a number of layers of leather or other yielding material adapted to strike against the shuttle, all as will be hereinafter fully explained, and specifically pointed out in the claims.

Reference is to be had to the accompanying drawings, forming a part of this specification, in which similar figures and letters of reference indicate corresponding parts in all the views.

Figure 1 is a sectional view of my improved picker as attached to the picker-staff. Fig. 2 is a face view thereof. Fig. 3 is a rear view of the same. Fig. 4 is a plan view of the picker and staff, and Fig. 5 is a view of the blank from which the picker-housing is formed.

In constructing the picker forming the subject-matter of this application, I provide a blank 10, of metal, preferably of steel, formed with an aperture *a*, with main wings *b b'*, adapted to fit against the sides of the picker-staff, and with auxiliary wings or leaves *c c'* and *d d' d'*, the leaves and wings being so proportioned that they may be bent and riveted to place, as represented in the drawings, the wings *b b'* and the leaves *c c'* being bent at right angles to the body, and the leaves *d d'* being bent at right angles to the wings *b b'* over the leaves *c c'*, the arrangement being such that a housing is formed, and within this housing I arrange

a number of layers of scrap-leather, such layers being shown at 11 in Fig. 1. The wings *b b'*, having been bent, as shown in Fig. 4, so as to fit closely against the picker-staff 20, a heavy rivet 12 is secured in the ends of the said wings. Between the wings when I apply the picker to the staff I place a heavy spring 14, which passes beneath the rivet or bolt 12 in a position to be borne upon by a locking-lever 15, which is formed with an eccentrically-recessed head 16, the head being arranged for engagement with the rivet or bolt 12, as is clearly shown in Fig. 1, the arrangement being such that by bringing the head 16 into engagement with the rivet or bolt 12 and then turning the lever 15 to the position in which it is shown in Fig. 1 the picker will be firmly locked to the staff.

By means of the picker and securing devices above described I dispense with the ordinary picker-loop, and also with the screw, by means of which pickers have heretofore been fastened to their staffs, and at the same time I am enabled to utilize scrap-leather which would otherwise go to waste.

The picker may be readily applied to the staff and adjusted to the required position, and as the leather layers 11 wear out they may be easily renewed.

Having thus described my invention, I claim as new and desire to secure by Letters Patent—

1. The combination, with a picker-staff, of a housing provided with wings connected by a rivet, a lever having an eccentric-head engaging the rivet of the housing, and a spring arranged between the eccentric-head and picker-staff, substantially as described.

2. In a picker, the combination, with a blank bent to form a housing, and having an aperture *a*, of a rivet or bolt 12, which passes through wings forming a portion of the blank, a spring 14, and an eccentric-headed locking-lever, substantially as described.

CORNELIUS CHIPPENDALE.
